SEPARATOR FOR PRODUCING DRY STEAM

William R. Williamson and John P. Tyskewicz,
Hartford, Conn., assignors to The Maxim
Silencer Company, Hartford, Conn., a corpora-
tion of Connecticut

Application March 20, 1951, Serial No. 216,558

16 Claims. (Cl. 183—89)

1

The present invention relates to a separator for producing dry steam from a mixture of steam and entrained water, and in particular to a separator for use with evaporators used for the distillation of sea water for the production of drinking water. In this case any water entrained in the steam passing from the evaporator to the condenser will carry with it dissolved salts which decrease the potability of the condensate. For an example of the type of evaporator and separator to be described, we refer to our co-pending application Serial No. 90,528.

The improvements to be described have for their object a greatly improved operation of the evaporator and separator, both in the purity of the potable water obtained and in the quantity produced per day by a given size of evaporator. We have found that a major problem in the design of separators is that of preventing re-entrainment of water once separated. Unless the separated water can at once enter a relatively quiet pool of water, it is liable to be forced into the steam stream and carried over into the condenser. Again, we have found that there is a tendency for a water drop to creep along an otherwise dry surface and make its way into the outlet conduit, where it is readily re-entrained.

In the construction shown in our co-pending application, above referred to, a chamber bounded by a vertical cylindrical wall and by upper and lower headers is provided with a tangential inlet for mixed steam and water. The steam and water are thus caused to whirl around within the chamber, the heavier water going to the outside and running down the cylindrical wall while the steam is left in the center. A vertical steam outlet conduit extends downwardly through the upper header and has an opening or window in its side through which steam can enter, this opening being surrounded by an out-turned flange or apron having the double purpose of streamlining the entrance to cut down resistance and blocking the entrance of water drops which may find themselves on the outside of the conduit. The bottom of the outlet conduit is closed, in the form shown in the application referred to, by a shallow conical plate reaching nearly to the cylindrical wall but stopping short of it so as to leave an annular gap through which water can descend to a receiving pool below. While this construction gives excellent performance, we have found that, when an attempt is made to increase the rate of steam flow through the separator beyond a certain point, water will creep along the surface of the

5 top header, thence down the outside of the outlet conduit, and will find its way into the window in spite of the apron. Likewise, stepped up operation results in water splashing onto and creeping along the top of the plate below the conduit, which has the function of protecting the separator chamber from the entrance of water drops thrown up by ebullience in the receiving pool. If water drops do get on top of the plate they tend to creep inwardly to the outlet conduit and when they reach it can, under conditions of high steam flow, get past the apron and through the window.

10 The construction shown in the present application avoids this creeping action to a remarkable degree, so that an increase in the maximum operating rate of a given separator of forty or fifty per cent may be attained. Furthermore, it is no longer necessary to employ two stages to produce the high degree of water purity required for drinking purposes.

15 For a detailed description of the invention we refer to the drawings, in which

20 Fig. 1 is a median vertical section through an evaporator and separator;

Fig. 2 is a section on line 2—2 of Fig. 1;

Fig. 3 is a section on line 3—3 of Fig. 1; and

25 Fig. 4 shows a detail of construction on an enlarged scale.

30 Since the heating section of the evaporator is substantially the same as that described in the application referred to above, the following description will be limited principally to the separating section lying above the plane X—X. The combined evaporator and separator comprises a generally cylindrical casing 10 with top and bottom headers 11 and 12 and an intermediate header 13 which divides the interior of the casing into a heating section 14 and a separating section 15. The heating section 14, which has been described previously in our prior application, delivers steam through the outlet pipe 16 to the top tangential inlet connection 17 of the separator section 15.

35 Depending from and supported by the top header 11, which is preferably domed upwardly as shown but which may be flat, is a steam outlet conduit 18 having a laterally disposed window-like opening 19 adjacent its lower end. The conduit 18 is closed off at its bottom end by a plate 20, which is of substantially greater diameter than the conduit and which also forms the bottom of the window-like opening 19. This opening is streamlined by an apron 21 as in said prior application, the apron serving to reduce

entrance losses at said opening and to afford some measure of protection against water creeping into the opening.

Suspended immediately below the plate 20 by a short collar 22 is a conical anti-flash plate 23, extending nearly to the cylindrical casing wall 10, but spaced from it to leave an annular gap 24, relatively narrow, through which water may pass into the receiving pool below. At a distance below the plate 23 approximately equal to four times the width of the gap 24 is a flat ring or annular plate 25 secured to the cylindrical wall of the separator chamber and extending inwardly a radial distance also approximately equal to four times the width of the gap. This ring prevents water from being thrown upwardly through the gap 24. The chamber or receiving pool between the ring 25 and the header 13 has anti-whirl vanes 26 in crossed formation and a float valve 27 respectively serving the same purposes as in our prior application.

Secured to the under side of the upper header 11 is a fin 28, which projects downwardly and is formed as a spiral progressing outwardly in a direction away from the tangential inlet 17. The purpose of this fin is to prevent water from reaching the outside of the outlet conduit 18. It accomplishes this result by leading out toward the casing wall 10 such water drops as may be splashed against the header 11 from the inlet 17. We have shown this spiral as having approximately one and a half convolutions. If the pitch of the spiral is too steep, water may be flung off the fin before it reaches the outer end, in which case it will be entrained immediately in the whirling steam and will pass through the window 19 and up the outlet conduit.

We have found that, in order to increase the efficiency of the separator by any substantial amount, it is necessary to keep all surfaces directly associated with the window 19 as nearly completely dry as possible. The fin 28 accomplishes this purpose in the upper part of the separator. To keep the bottom part of the outlet conduit 18, the plate 20, and the top of the anti-flash plate 23 essentially dry, it is necessary to reduce, but without turbulence, the angular velocity of the steam in the lower part of the separator. This is accomplished in the present embodiment by four anti-whirl blades or vanes 29 which are in the form of straight strips supported above the surface of the plate 23 by tabs 30. The four vanes 29 also reduce the back pressure of the device by reducing the whirling of the steam before it passes into the outlet conduit. Additionally, the slant given to the vanes creates a down draft over the surface of the plate 23, so that any water droplet entrained in the whirling steam will be thrown down upon the plate and thus prevented from reaching the window 19.

It is emphasized again that the successful functioning of the separator at high output rates is largely dependent upon keeping the surfaces of members 18, 20 and 23 substantially dry. In the case of accidental wetting of the plate 23 due to momentary overloads or splashing, there is, due to the presence of plate 20, a limit to the distance inwardly to which the unbalance of the centrifugal forces at the top and the bottom of the separator can cause such water to move. The tendency for water to move inwardly along plate 23 is analogous to the collection at the center of a beaker of a precipitate when the liquid in the beaker is stirred in one direction. There is outward movement at the top, downward move-

ment along the walls, inward movement at the bottom, and upward movement near the center. By preventing the upward movement within an area larger than the outlet conduit, the plate 20 restricts the inward movement at the bottom as well, and thus keeps any water drops on plate 23 out of the region in which they might reach the outer surface of the outlet conduit. Relatively large amounts of water may collect underneath the ring 25 and be evaporated or flung off without ever reaching the window-like opening 19. In fact when small amounts of water are on the plate 23 they never even reach the collar 22. The plate 20, therefore, may be considered as affording an additional measure of protection against contamination of the steam leaving the chamber.

By having the interior of the outlet conduit 18 terminated at its lower end by the imperforate plate 20, there is eliminated any pocket within the conduit in which any appreciable quantity of water could accumulate. This is a great advantage in quickly clearing the separator of contaminated water following any accidental incorrect adjustment or malfunctioning of the controls.

What we claim is:

1. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate positioned below the outlet conduit with its outer edge spaced from the cylindrical wall to leave an annular gap; said separator having in combination therewith a series of substantially radial vanes positioned above but spaced from said plate and slanted downwardly in a direction away from the tangential inlet.

2. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate positioned below the outlet conduit with its outer edge spaced from the cylindrical wall to leave an annular gap; said separator having in combination therewith a series of substantially radial vanes positioned above but spaced from said plate and slanted downwardly in a direction away from the tangential inlet, and an annular ring secured to the cylindrical wall of the chamber below said annular gap and of a radial width greater than said gap.

3. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate positioned below the outlet conduit with its outer edge spaced from the cylindrical wall to leave an annular gap; said separator having in combination therewith a series of substantially radial vanes positioned above but spaced from said plate and slanted downwardly in a direction away from the tangential inlet, the upper header of the chamber being upwardly domed, and a fin secured to the under side of said header, projecting downwardly therefrom, and formed as

a spiral progressing outwardly in a direction away from the tangential inlet.

4. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate positioned below the outlet conduit with its outer edge spaced from the cylindrical wall to leave an annular gap; said separator having in combination therewith a series of substantially radial vanes positioned above but spaced from said plate and slanted downwardly in a direction away from the tangential inlet, and a fin secured to the under side of the upper header, projecting downwardly therefrom, and formed as a spiral progressing outwardly in a direction away from the tangential inlet.

5. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate positioned below the outlet conduit with its outer edge spaced from the cylindrical wall to leave an annular gap; said separator having in combination therewith an annular plate secured to the cylindrical wall of the chamber below said annular gap and of a radial width greater than said gap, the upper header of the chamber being upwardly domed, and a fin secured to the under side of said header, projecting downwardly therefrom, and formed as a spiral progressing outwardly in a direction away from the tangential inlet.

6. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate positioned below the outlet conduit with its outer edge spaced from the cylindrical wall to leave an annular gap; said separator having in combination therewith an annular plate secured to the cylindrical wall of the chamber below said annular gap and of a radial width greater than said gap, and a fin secured to the under side of the upper header, projecting downwardly therefrom, and formed as a spiral progressing outwardly in a direction away from the tangential inlet.

7. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate positioned below the outlet conduit with its outer edge spaced from the cylindrical wall to leave an annular gap; said separator having in combination therewith a series of substantially radial vanes secured to and spaced from the upper surface of said plate and slanted downwardly in a direction away from the tangential inlet, an annular plate secured to the cylindrical wall of the chamber below said annular gap and of a radial width greater than said gap, the 75

upper header of the chamber being upwardly domed, and a fin secured to the under side of said header, projecting downwardly therefrom, and formed as a spiral progressing outwardly in a direction away from the tangential inlet.

8. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate positioned below the outlet conduit with its outer edge spaced from the cylindrical wall to leave an annular gap; said separator having in combination therewith a series of substantially radial vanes secured to and spaced from the upper surface of said plate and slanted downwardly in a direction away from the tangential inlet, an annular plate secured to the cylindrical wall of the chamber below said annular gap and of a radial width greater than said gap, and a fin secured to the under side of the upper header, projecting downwardly therefrom, and formed as a spiral progressing outwardly in a direction away from the tangential inlet.

9. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end and having an opening in its side; said separator having in combination therewith a fin secured to the under side of the upper header of said chamber, projecting downwardly therefrom, and formed as a spiral progressing outwardly in a direction away from the tangential inlet.

10. A separator as claimed in claim 9 in which the upper header of the chamber is domed upwardly.

11. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end and having an opening in its side; said separator having in combination therewith a fin secured to the under side of the upper header of said chamber, projecting downwardly therefrom, and formed as a spiral progressing outwardly in a direction away from the tangential inlet, said fin being spaced from the outlet conduit and from the cylindrical wall of the chamber at its inner and outer ends respectively.

12. A separator as claimed in claim 11 in which the upper header of the chamber is domed upwardly.

13. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate positioned below the outlet conduit with its outer edge spaced from the cylindrical wall to leave an annular gap; said separator having in combination therewith a second plate between the first plate and said side opening and having a diameter less than that of the first plate but greater than that of the outlet conduit.

14. A separator of the type having a vertical cylindrical wall and headers forming a chamber, an inlet for mixed steam and water leading tangentially into said chamber to cause whirling, an upwardly directed outlet conduit for steam substantially coaxial with the chamber and having an opening in its side adjacent its lower end, and a plate positioned below the outlet conduit with its outer edge spaced from the cylindrical wall to leave an annular gap; said separator having in combination therewith a second plate between the first plate and said side opening and having a diameter less than that of the first plate but greater than that of the outlet conduit, said second plate being positioned to close off the lower end of the outlet conduit and to form the bottom edge of said side opening.

15. A separator of the type having a vertical cylindrical wall and headers forming a chamber, an inlet for mixed steam and water leading tangentially into said chamber to cause whirling, an upwardly directed outlet conduit for steam substantially coaxial with the chamber, closed at its lower end, and having an opening in its side, and a plate in the form of a flat cone positioned below the outlet conduit with its outer edge spaced from the cylindrical wall to leave an annular gap; said separator having in combination therewith a second substantially flat plate between the conical plate and said side opening and having a diameter less than that of the conical plate but greater than that of the outlet conduit.

16. A separator of the type having a vertical

cylindrical wall and headers forming a chamber, an inlet for mixed steam and water leading tangentially into said chamber to cause whirling, an upwardly directed conduit for steam substantially coaxial with the chamber and having an opening in its side adjacent its lower end, and a plate in the form of a flat cone positioned below the outlet conduit with its outer edge spaced from the cylindrical wall to leave an annular gap; said separator having in combination therewith a second substantially flat plate between the conical plate and said side opening and having a diameter less than that of the conical plate but greater than that of the outlet conduit, said second plate being positioned to close off the lower end of the outlet conduit and to form the bottom edge of said side opening.
